Specification for Design.

Patented June 17, 1919.

Application filed May 7, 1918. Serial No. 233,155. Term of patent 3½ years.

To all whom it may concern:

Be it known that I, WALBORG AHLMGREN, a citizen of Sweden, and resident of the borough of Manhattan, in the county, city, and State of New York, have invented a new, original, and ornamental Design for Game-Boards, of which the following is a specification, reference being had to the accompanying drawing, forming a part thereof.

In the said drawing:—

The figure is a front view of a game board, showing my new design.

I claim:—

The ornamental design for a game board as shown.

In testimony whereof I have signed my name to this specification in the presence of a subscribing witness.

WALBORG AHLMGREN.

Witness:

H. C. KARLSON.
